ELECTRICAL CONNECTER

Edwin C. Winslow, Jr., Mattapoisett, Robert F. Wilder, South Dartmouth, and Charles W. Smith, New Bedford, Mass.

Application October 13, 1934, Serial No. 748,158

5 Claims. (Cl. 173—273)

This invention relates to electrical connectors and has for its principal object to provide a new and improved structure for a connector of the type particularly adapted for use for making connections to electric wires or cables carrying high voltages and where it is desired to make a connection to the line in a safe and efficient manner while the current is flowing through such line.

10 Although we are aware that it is not broadly new to employ two part insulated connectors, such devices as heretofore constructed have been of relatively complicated construction and therefore expensive to manufacture and have generally been of the type limited in their application to the making of a connection between the ends of a pair of wires. Prior devices wherein joints were made between the ends of the wires to be connected are difficult to assemble and their use 15 is attendant with considerable hazard particularly for high voltage lines, due to the fact that they are not sufficiently insulated and that there is always the danger of a lineman's hands or body coming into contact with an exposed conductor. It is therefore an important object of 20 the present invention to provide a construction in which these objectionable features are obviated.

It is another object of the present invention 25 to provide a new and improved connector which can be employed with equal facility for tapping a line without severing the wire or cable or joining the broken ends of a severed line.

A further object of the present invention is 30 to provide a new and improved construction of an electrical connector in which all of the metallic conductor parts are fully and completely sheathed by highly efficient insulated covers which are so associated with the metallic elements as to be readily detachable therefrom to enable the latter to be secured in electrical conducting relationship with the wires or cables to be united.

The above and other objects of the present invention will appear more fully from the following more detailed description by reference to the accompanying drawing forming a part thereof wherein:

50 Fig. 1 is a central longitudinal section through an electric connector constructed in accordance with the principles of the present invention;

Fig. 2 is a perspective view on a smaller scale illustrating the method of assembling the connector shown in Fig. 1;

Fig. 3 is a section taken substantially on the line 3—3 of Fig. 1;

Fig. 4 is a side elevation of one of the metallic conductor parts of the connector; and

Fig. 5 is a central longitudinal section through 5 the insulating sheath of the connector part shown in Fig. 4.

As shown in the drawing, the main conducting element of the connector consists of a body part 10 constructed of copper, brass or other material having high electrical conductivity. The body 10, while shown in the drawing as being approximately cylindrical in shape, may be of any desirable or suitable configuration to provide a sufficient mass of material which can be cut 15 away to form a hook-shaped slot 11 in the body 10 of sufficient size to permit the engagement of such slot over a wire or cable 25 of the largest size for which the particular connector is intended for use. One end of the slot 11, as clearly 20 shown in Figs. 1, 2, and 4 of the drawing, is open on one side of the body 10 at a point between ends of said body, as indicated by the reference character 11a, and the other end of the slot terminates in a wedge-shaped pocket 11b located 25 approximately midway between the ends of the body 10 and which extends transversely or diametrically across said body with the smaller end or point of the wedge-shaped pocket crossing the central axial line of the body 10. As will be 30 clearly seen from Fig. 2 of the drawing, the arrangement of the slot 11 is such that the body member 10 of the connector may be slipped over a cable 25 at any point along such cable without necessitating any cutting of the cable and so that 35 after the open side of the pocket is placed over the cable, the body 10 of the connector may be moved so as to cause the cable to be seated within the wedge-shaped pocket 11b.

That end of the body 10 next to the slot 11 40 is provided with a screw threaded hole 12 adapted to receive a clamping bolt or screw 13 which is provided with a non-circular bolt head 14 held fast within a cooperating non-circular recess formed in the main body portion of an insulating 45 shell 15 which is preferably constructed of soft rubber, the shell 15 preferably being associated with the bolt 13 by casting or molding the shell 15 on the bolt. As clearly shown in Fig. 1 of the drawing, the shell member 15 is provided with a 50 flange portion 15a which, when the bolt 13 is screwed into the hole 12 and with the end of the bolt 13 in clamped engagement with the cable 25, will completely cover the open end 11a of the slot 11.

The end of the body 10 farthest from the slot 11 is provided with a hole or bore 16 to receive the end of a wire or cable, which wire or cable may be tightly secured in said hole 16 either by 5 soldering, or one or more holes 17, 17' may be drilled and tapped into the body 10 at right angles to the hole 16 for the reception of set screws 18, 18' by means of which the end of the wire inserted into such hole may be clamped securely 10 in position and in conducting relationship with the body 10.

The body 10 is completely enclosed and insulated by a sheath 19 of insulated material which preferably is constructed of soft rubber having a 15 relatively solid end of portion 19^a formed with a hole 21 in axial alignment with the hole or bore 16 of the body 10 through which hole 21 a cable, such as indicated by the reference character 22, can be inserted into the bore 16.

20 Due to the fact that the connector parts consisting of two assembly units, one comprising the bolt 13 and shell 15 and the other the body 10, and sheath 19, are assembled together to form a connection by relatively rotating the two parts 25 to engage the bolt 13 in clamped relationship with the cable 25, means are preferably provided for holding the sheath 19 against rotation relatively to the body 10 and such means may comprise a flattened or non-circular portion 23 formed on 30 the end of the body 10, which is adapted to be received within a similarly fashioned recess 23^a formed in the sheath 19 adjacent the thickened end 19^a thereof.

For the purpose of insuring a more secure engagement of the rubber sheath 19 with the body, also for providing a safer and more effective insulation, that portion of the sheath 19 which is 35 cut away to form a slot of similar configuration to the slot 11 is provided with an inwardly extending flange 19^b shown best in Fig. 4 of the drawing, which is adapted to be received within a recess 20 formed in the body 10; it being understood that the recess 20 extends continuously about the side edges of the slot 11 as indicated in 40 Fig. 4 of the drawing and that the flange 19^b is continuous and extends about the similarly shaped slot in the rubber sheath 19. That end of the body 10 which is screw threaded for the reception of the bolt 13 is also cut away to provide 45 an annular recess 26 with which is adapted to engage an annular flange 27 that projects inwardly from the end of the sheath 19, the engagement of the flange 27 with the recess 26 being similar to the engagement of the flange 19^b with the recess 20. As the result of the provision of 50 the flanges 19^b and 27 upon the sheath 19 and the engagement of these flanges with their cooperating recessed portions of the body 10, the sheath 19 is associated in interlocked relationship with 55 the body, the flanges not only serving to assist the parts 23, 23^a in preventing relative rotation between the insulating sheath and conductor body 10 but also to prevent any longitudinal displacement 60 between the parts. Moreover, the provision 65 of the inwardly turned flanges of the sheath will insure a tighter clamping of the sheath upon the conductor and serve to hold the sheath in snug clamped engagement upon the conductor. Furthermore, the flanges 19^b and 27 insure the provision 70 of a thicker wall of insulation around the open edge of the slot 11 as well as the end of the body 10 with which the bolt 13 is engaged.

The manner in which the device is employed is as follows:

75 If a connection is to be made to a continuous

cable without cutting or severing said cable, the rubber sheath 19 is stripped from the connector body 10. This can readily be done by turning back to one side the portion 24 of the sheath 19 and disengaging the flange 27 and the adjacent end of the flange 19^b from the shouldered or recessed portion 20 of the body 10. The other edges of the flange 19^b can then be turned back out of engagement and the conductor 10 pulled axially from the sheath. A cable, such as cable 22 which it is desired to connect to the cable 25, after having its insulation removed is then inserted into the bore 16 of the conductor body, the rubber sheath 19 first having been slipped over the cable 22. The exposed end of the cable 22 can then be 15 soldered tightly in the hole 16 and the set screws 18, 18' screwed into clamped engagement with the end of the cable 22. The conductor body 10 is then reinserted into the sheath 19 with the flattened ends 23 of the conductor body in engagement with the cooperating recess 23^a of the sheath. The end 24 of the sheath is then pulled over the other end of the body 10 and so that the flanges 19^b and 27 will snap into engagement with the recesses 20 and 26. At the point where 25 it is desired to make the connection to the cable 25, the insulation is stripped from such cable and the insulated conductor 10 having the cable 22 secured thereto is placed over the cable 25 so that the latter will enter the open end 11^a 30 of the slot after which the conductor body 10 is moved axially to cause the cable 25 to seat in the wedge-shaped pocket 11^b. The threaded end of bolt 13 carried by the rubber shell 15 is then threaded into the hole 12 in the end of the body 35 10 and the bolt is screwed home into clamping engagement with the cable 25, the flange 15^a of the shell 15 telescoping over the rubber sheath 19 and covering the open side 11^a of the slot 11.

As will be seen from the foregoing, the complete insulation, both of the bolt 13 and the conductor body 10 by the insulating members 15 and 19, enables the connection to be made in the manner just described without the lineman being required to bring any part of his hands or body 45 in contact with any exposed conductors, the sheath 19 being grasped in one hand at its thicker end and at a point quite some distance removed from the slot 11 and the shell 15 being grasped at its lower end where a solid mass of rubber is 50 interposed between the hand of the workman and the bolt 13.

It will, of course, be understood that while the device may be readily used to make a connection to a continuous or unsevered cable, it can 55 just as readily be used for connecting the two ends of a broken cable. The construction is of marked simplicity. The conductor body 10 may be constructed as a casting which will require but very little or no machining to place it in finished 60 condition.

The device has proven highly successful in practice for tapping high voltage lines, a connection being made very quickly as the complete insulation of the connector enables a lineman to 65 work with much greater speed than would otherwise be possible, especially on high voltage lines, without endangering himself to severe shocks.

The device has been found highly satisfactory for jumping faulty cutouts; temporarily connecting secondaries; jumping out street light fixtures which are giving trouble; temporarily repairing broken taps or junction poles on either primary or secondary or street lights; transferring construction from old poles to new especially where 75

the heights of the poles are to be changed or on dead end construction. The connector may also be employed in sub-station work for short circuiting current transformers, making temporary 5 connections, etc., and in power stations for meter testing; has proven satisfactory in use for clearing troubles in street light lines, cutting over junction poles and changing dead ends which have always been extremely hazardous jobs with 10 the type of connectors heretofore employed.

While we have described and illustrated a satisfactory installation that has proven highly successful in practical operation, it will be understood that the invention is not limited to specific 15 constructional details shown and described, but that many changes, variations and modifications may be resorted to without departing from the principles of the invention.

We claim:

1. An electrical connector comprising a conductor body formed of material having high electrical conductivity and having formed therein a pocket extending transversely across said body for the reception of an electrical conducting line, 25 said pocket terminating at one end in a wedge shaped seat and at its other end in an open ended slot, said body having at one end thereof a screw threaded opening adjacent and extending laterally to said pocket, a clamping element for engagement with said screw threaded opening adapted to project into said pocket to engage said conducting line and clamp it securely against said wedge shaped seat and the other end of said conductor body being provided with means for receiving and clamping a second conducting line 30 in electrical contacting engagement with said body, an insulating sheath encasing said conductor body, said sheath having a cylindrical outer periphery and having formed therein an opening of similar configuration to the pocket formed in said conductor body and a second opening through which said second conducting line extends and an insulating shell having an annular portion in which said clamping element is non- 35 rotatably secured having a projecting skirt portion which surrounds said clamping element and covers said slot when said shell is assembled with said body.

2. An electrical connector comprising a conductor body formed of material having high electrical conductivity and having formed therein a pocket extending transversely across said body for the reception of an electrical conducting line, 40 said pocket terminating at one end in a wedge shaped seat and at its other end in an open ended slot, said body having at one end thereof a screw threaded opening adjacent and extending laterally to said pocket, a clamping element for engagement with said screw threaded opening adapted to project into said pocket to engage said conducting line and clamp it securely against said wedge shaped seat and the other end of said conductor body being provided with means for receiving and clamping a second conducting line 45 in electrical contacting engagement with said body, an insulating sheath encasing said conductor body, said sheath having formed therein an opening of similar configuration to the pocket formed in said conductor body and a second opening through which said second conducting line 50 extends and an insulating shell in which said clamping element is non-rotatably secured, and said shell having an annular flange in spaced concentric relationship with and projecting beyond said clamping element adapted to telescopically 55

engage over said insulating sheath and to completely close said open-ended slot when said clamping element is clamped against said conducting line.

3. An electrical connector comprising a conductor body formed of material having high electrical conductivity and having formed therein a pocket extending transversely across said body for the reception of an electrical conducting line, 60 said pocket terminating at one end in a wedge shaped seat and at its other end in an open ended slot, said body having a screw threaded opening extending laterally to said pocket, a clamping element for engagement with said screw threaded opening adapted to engage said conducting line and clamp it securely against said wedge shaped seat, a flexible insulating sheath detachably mounted upon and encasing said conductor body, said sheath having formed therein an opening of similar configuration to the pocket formed 65 in said conductor body, said body having an inwardly extending recess in its periphery extending inwardly from and about the entire bounding edge of said slot and said sheath having an inwardly projecting flange seated within said recess.

4. In an electrical connector, a conductor body formed of material having high electrical conductivity having a pocket therein extending partly transversely across said body for the reception 70 of an electrical conducting line, which pocket terminates at one end in a wedge shaped seat and at its other end in an open ended slot, said body having a screw threaded opening extending laterally to said pocket, a clamping element engageable with said screw threaded opening to clamp said conducting line securely against said wedge shaped seat, a flexible insulating sheath for detachably encasing said conductor body, said sheath having formed therein an opening of similar configuration to the pocket formed in said conductor body, said body having an inwardly extending recess bounding the entire outline of said pocket and slot and said sheath having a projecting rib seating within said recess, an insulating member non-rotatably mounted on 75 said clamping element having an annular sleeve-like portion surrounding said element in spaced concentric relationship with and projecting beyond said element and adapted to telescopically engage over said insulating sheath and to completely close said open ended slot when said clamping element is clamped against said conducting line and said sheath being provided at one end with cooperating non-circular parts to prevent relative rotation between said body and sheath.

5. An electrical connector comprising a conductor body formed of material having high electrical conductivity and having formed therein a pocket extending partly transversely across said body for the reception of an electrical conducting line, 80 said pocket terminating at one end in a wedge shaped seat and at its other end in an open ended slot, an inwardly recessed portion extending around the entire bounding edge of said pocket and slot and a screw threaded opening extending laterally to said pocket, a clamping element for engagement with said screw threaded opening adapted to engage said conducting line and clamp it securely against said wedge shaped seat, a flexible cylindrical insulating sheath detachably mounted upon and encasing said conductor body, said sheath having formed therein an opening of similar configuration to the pocket 85

formed in said conductor body, an inwardly projecting flange for engagement with said recess, said body being provided at one end thereof with an opening for a second conducting line and means for securing the latter to said body, said body and sheath being provided with inter-engaging non-circular means to prevent relative rotation therebetween and said clamping element being provided at one end with a non-circular enlarged head and an insulating member in which

said head is embedded having an annular flange concentrically spaced from and projecting beyond the other end of said clamping element, said flange telescopically engaging over said sheath and completely closing said open ended slot when said element is in clamped engagement with said body. 5
